UNITED STATES PATENT OFFICE.

EINAR LESCHBRANDT, OF PHILADELPHIA, PENNSYLVANIA.

PHOTOGRAPHIC CAMERA.

1,278,692.

Specification of Letters Patent. Patented Sept. 10, 1918.

Application filed November 25, 1914. Serial No. 873,856.

To all whom it may concern:

Be it known that I, EINAR LESCHBRANDT, a resident of the city of Philadelphia, county of Philadelphia, State of Pennsylvania, have 5 invented certain new and useful Improvements in Photographic Cameras, of which the following is a specification.

My invention relates to improvements in photographic cameras and the object of my 10 invention is to furnish in connection with a camera a means whereby a person without special skill or practice can print in type a suitable title or inscription upon the film or plate.

15 In carrying out my invention I furnish a means whereby the title can be placed symmetrically appearing upon the negative, a means whereby the letters may be evenly spaced and alined, and a means whereby the operator may bring any particular letter rapidly to its appointed position.

20 My invention is illustrated in the accompanying drawings in which similar numerals of reference indicate similar parts throughout the several views and in which—

Figures 1 and 2, are, respectively, a top plan and a side elevation of a camera case embodying my improvements:

25 Fig. 3, a top plan view of a camera, partly broken away, to show the shield and curtain actuating mechanism and the shield and curtain:

Fig. 4, a section of Fig. 3 on line A—A some parts of the mechanism connected 30 therewith being removed:

Fig. 5, a section of Fig. 3 on line B—B:

Fig. 6, a section of Fig. 3 on line C—C:

Fig. 7, a plan of part of camera back showing slotted tongue:

40 Fig. 8, a plan of part of film and light proof paper backing adapted for use in my camera:

Fig. 9, an enlarged sectional view of working end of camera on line A—A, Fig. 3 showing the shutter closed:

Fig. 10, a similar view showing the shutter open:

Fig. 11, a plan of means for actuating window carrying shield with a step by step 45 movement:

Fig. 12, a similar view showing the mechanism in its second position:

Fig. 13, a perspective view of shutter and connected parts:

55 Fig. 14, a plan of window carrying curtain or shield:

Fig. 15, a plan of letter or character carrying curtain:

Fig. 16, a side elevation of one of these 60 curtains:

Fig. 17, a plan of a modified form of letter or character carrying curtain;

Fig. 18, a plan of a shield adapted to be used in connection with the curtain shown in Fig. 17:

Fig. 19, a plan of part of camera showing the curtain and shield of Figs. 17 and 18 in position for operation.

Referring to Figs. 3, 4 and 5, 1 are parallel strips of metal secured upon opposite sides 70 to the inner part of the camera back or lid 2. 3, best shown in Fig. 5, is a plate of metal secured to the under sides of strips 1, there being thus formed a support for, and means to guide the movement of, the character 75 bearing curtain 5 and the shield 4, these being situated between the plate 3 and camera back 2. As I prefer to print the inscription by means of photographic exposure and directly upon the film or plate of the camera, 80 the types or patterns with which the printing is done, and which represent the letters of the alphabet, or other characters, are formed on transparent material, preferably flexible, such as celluloid for instance, and 85 the characters thereon may be either opaque on transparent ground, or vice versa, forming, in either case, light pervious patterns. These are best seen in Fig. 15 where 5 is a curtain having the patterns or characters 90 thereon disposed in a series of straight and parallel rows, there being in each row a set of the letters which constitute the alphabet, and also figures and punctuation marks.

The purpose of this curtain, hereinafter 95 called the type curtain or simply the curtain, is to form photographic images of its separate characters upon the film or plate carried by the camera when light is admitted through them. In the particular form 100 of my invention as described in this application, which form may be considerably modified without departing from the spirit of my invention, it is necessary during the selective compounding of characters that only one 105 single character on the type curtain pass light at one time as the apparatus is so designed that the title or inscription is printed letter by letter when exposure is made partly by means of the slot 6, Figs. 3, 4, 7, 9 and 10 110 and partly by the spacing shield 4, which is of opaque or red material furnished with a

diagonal line of transparent squares or windows *a—a—a* best shown in Fig. 14, which lies over the type curtain, each square being adapted to pass light at one time to but one of the characters of the type curtain, the opaque part of the shield blanketing all other characters.

While I have shown a diagonal or oblique row of transparent openings it will be understood that if these openings were merged into one so as to form a long, transparent, obliquely placed slot it would act in the same manner, and I make no distinction between a row of openings as shown in the spacing shield 4, Figs. 3 and 14, and a single opening, successively used, as shown in the modification.

The parts 4—5 have one of their longitudinal edges smooth and the other furnished with teeth or notches, for instance the right hand side of curtain 5 and the left hand side of shield 4 are notched and these notches are adapted to be engaged by toothed wheels 7—8 respectively. These wheels are shown in Figs. 3, 6, 11, and 13. By turning wheel 7 type curtain 5 may be moved longitudinally and by turning wheel 8 the spacing shield 4 may be similarly moved.

Fig. 6 is an exaggerated sectional view on line C—C of Fig. 3 showing a thin strip of metal 9 separating the spacing shield from the type curtain so that each may properly engage with its toothed actuating wheel. 10 is a thin piece of metal beneath the type curtain 5, 11 a partition separating pieces 9 and 10 at one end and engaging the smooth side of the type curtain to hold its toothed side in engagement with teeth of wheel 7. 12 a similar partition separating plate 9 and camera back 2 and serving the same purpose with respect to shield 4 as does piece 11 to curtain 5.

13—14 are lugs on plates 9 and 10 which engage opposite sides of the type curtain 45 near its toothed edge to hold the teeth in proper engagement with the teeth of wheel 7. Similar lugs 15 on back 2 and plate 9 serve the same purpose for the toothed edge of shield 4.

50 The wheel 7 is fitted with a shaft 16 which carries a milled wheel 17 and the shaft 16 of wheel 8 carries a wheel 18, the wheels 17—18 being upon the outside of the camera back 2, and by means of these wheels the toothed wheels 7—8 may be turned by hand to slide the parts 4—5 forward or backward. When moved forward their forward ends enter the curved chamber at the end of the camera and will thereby be bent around the 60 cartridge or film roll 19, Figs. 4, 9 and 10, thus being taken care of. By further reference to Figs. 9 and 4 it will be seen that the curtain and shield pass over a table 22, formed by the lower end of the head frame 65 21 of the camera, over which, also, passes

the photographic film 20. The frame 21—21 forms the opening through which light is admitted from the regular lens of the camera in the photographing of pictorial views on the film, the latter being a strip of the usual 70 length to permit the exposure of a series of views.

Above the table 22 the back 2 of the camera carries a tongue 23, which may be cut from the metal of the back as shown in Fig. 7, which has a sort of T shape in the free end or head of which is formed a slot 6. The head of this tongue can be pushed downward and it will return to its first position upon the pressure being relieved.

80 The slot 6 in the head of tongue 23 extends transversely of the back 2 and is wide enough to expose one row of letters, namely one letter out of each of the longitudinal rows on the type curtain, and long enough 85 to contain the several letters forming a title and is directly above the table 22. When the tongue 23 is pressed down it contacts with the shield 4 and presses the curtain 5 against the film 20, a condition desirable 90 for sharp printing, the spacing shield cutting out the entire row of characters which is in register with the slot except the one character below the particular transparent window *a* of the shield which also registers 95 with the slot.

By using the expression "registering with the slot" or similar expression in this specification and claims, I mean when referring to letters, that they record with the slot or 100 are placed opposite same so that light can pass through to print them on the light sensitive sheet.

A photographic camera constructed according to my invention may be a plate-holder or other camera or holder for photographic material, but the invention is particularly adapted for its embodiment in the film-roll or folding type of camera shown, and the printing of letters does not depend on whether or not the usual bellows extension at the front, fragmentarily shown in Fig. 4, is in position of contraction or expansion.

115 The pitch of the notches or teeth upon the edges of parts 4—5 are equal to the height of the windows *a* in the shield 4 so that every time the latter is moved one tooth successive windows *a* are brought to the slot 6. As the windows *a* are placed in a 120 diagonal line, each successive one being spaced so that they will uncover letters from left to right in proper spacing to properly form words, the window of spacing shield every time that it is advanced one tooth will 125 be in position to expose to the light successive letters along the line of the slot 6. The type curtain being similarly arranged, each tooth or notch on its edge corresponding to a row of characters, each time that it is ad- 130

- vanced a tooth will bring a new row of characters along the slot 6, one of these characters being in register with the window *a* in the spacing shield that is beneath slot 6. The parts 4—5 are independently movable and any desired character upon the type curtain may be brought in register with the window *a* on the shield that is beneath slot 6.
- 10 The arrangement of a lineally formed passage or opening, such as the slot 6, and the longitudinal character rows, whereof each has letters making up a complete alphabet, movable in a path of travel which is transverse to the length or line of the opening, enables the operator to selectively bring into printing position along the opening a letter of the first longitudinal row, a letter of the adjacent row to the right, and so on, exposing the film or other sensitized element to these master-letters so as to form words in definite relation with the previously photographed picture, the selective adjustment being made more easy by the arrangement whereby succeeding letters in any one longitudinal row stand above one another in the regular *a—b—c* order of alphabetic progression, as they may then pass the slot in a sequence always familiar to an operator.
- 30 I have used in this specification and in the claims such terms as slot, elongated aperture, elongated opening, as more or less synonymous terms, meaning to cover thereby any lineal opening formation. A lineally formed passage or a lineally formed opening are terms also intended to signify a lineal opening formation.
- It is desirable that the type curtain and shield be so arranged as to expose their characters and windows correctly below slot 6 and for this purpose I use springs 24 to engage the teeth of wheels 7—8 in such a manner as to stop these wheels in proper position to register the letters carried by the curtain and the windows carried by the shield.
- 40 Directly above slot 6 in tongue 23 is a similar slot 26 in a cap 27 which is carried by the back 2. The cap 27 carries a shutter 25 adapted to be passed between slots 26 and 6 so that no light may pass through the latter. This shutter is U shaped one leg closing slot 26 the other slot 6 as shown in Figs. 9 and 10. Near one end the shutter has an extension 28, best shown in Fig. 13, which is furnished with a slot 29 and a raised lip or pin 30 and a spring tongue 31. In the back of the camera is carried a pin 32 which enters slot 29 in projection 28 and serves as a guide for this projection in its movements.
- 50 33 is a lever pivoted at 34 and furnished at its free end with a slot 35 to receive the lip or pin 30 carried by projection 28. 36 is a push button projecting up through the top of case 27 the lower end of which carries a wedge 37, shown best perhaps in Figs. 9 and

10, which bears against the side of lever 33 and which upon being depressed will move the free end of the lever 33, Fig. 13, to the left which will in turn move the projection 28 and shutter 25 with it opening slots 26 and 6 to the light.

Attached to the button 36 is a stiff piece of metal 38, Figs. 3 and 6, the ends of which are bent down so as to engage the sides of the tongue 23 when the button 36 is depressed and move the free end of this tongue down to the position shown in the enlarged view Fig. 10 in order to hold the shield and type curtain and the film 20 close together and against the table 22. This is desirable in order that the characters on the type curtain may be printed upon the film without blurring.

When the pressure of the finger against the button 36 is relieved the button will be raised owing to the elasticity of tongue 23 and a spring 39 operating against the outer side of lever 33 will return this lever, the projection 28, and the shutter 25 to their first position shown in Fig. 9 in which the shutter closes the openings 26 and 6.

In addition to operating the shutter 25 and connected parts as described above, pushing button 36 accomplishes still another function, namely the movement of the shield one notch so that the next window on this shield will be brought to the next proper space to the right to expose the next succeeding letter of the title to the action of the light.

This movement of the shield is performed by the return movement of the spring tongue 31 which, when the wedge on button 36 is released, moves with the lever 33 and shutter 25 inward, engages a tooth on wheel 18 and moves this wheel so that the wheel 8, which actuates the shield, will be moved a distance sufficient to move the window in the shield 4 that is beneath slot 6 away from this slot and the next adjacent window into register with this slot. The spring tongue 31 has to be moved both backward and forward in contact with wheel 18. At the shutter's closing movement the tongue actuates the wheel. At its opening movement it slides past the wheel and at the same time provision must be made to turn the wheel 18 by hand either backward or forward without its being locked by the spring tongue, and this is accomplished as follows, references being had to Figs. 11, 12 and 13:

A spring detent 24 engaging the teeth of wheel 18 normally holds this wheel from movement when the shutter 25 is opening slots 26 and 6. The spring tongue 31 has a cut out portion 40 and a flat outer end 41 which when shutter 25 is closed rests against a tooth 18^a of wheel 18 as shown in Fig. 11 and in this position the wheel 18 can be moved in either direction. When the shut-

100

105

110

115

120

125

130

ter 25 is moved to the left to open slots 26—6 the spring tongue takes the position shown in Fig. 12. The part 41 of the tongue has now passed tooth 18^a and the cut 40 in the tongue 5 is opposite this tooth which passes through it as shown in Fig. 12. When, now, the button 36 is released and the shutter 25 is moved to the right to close slots 26—6 as previously described the outer end of the cut 10 out part 40 of the tongue 31 will engage the tooth 18^a and will move the wheel 18 the space of one tooth in the direction of the arrows Figs. 11 and 12. As the wheel 18 turns the next tooth 18^b will come up against the 15 flat end 41 of tongue 31 and in its circular swing will move the tongue out to the position shown in Fig. 11.

By reference to Figs. 1 and 6 it will be seen that the wheels 17—18 project slightly 20 outside the cap 27, the sides of the cap being appropriately slotted for this purpose, so that these wheels can be turned by the finger in order to set the spacing shield and the type curtain.

25 It is necessary that the operator should know what character he places before the exposure slots 26—6 and for this purpose I place in the back 2 of the camera a slot 42, Fig. 1, through which may be seen the extreme right hand row of characters on the type curtain 5. As the shield preferably 30 lies over the type curtain and is mostly opaque I leave a transparent band 43 on the right hand side of this shield, as shown in Fig. 14, through which this row of characters may be seen. For convenience sake the slot 42 in some distances away from the exposure slots 26—6 and it is therefore necessary that similar characters in the row 35 reserved for sight be correspondingly away from similar rows reserved for photographic exposure. In other words when a certain character is seen at the center of slot 42 a row consisting of similar characters are in 40 register with slots 26—6.

There is also placed in the camera back 2 a slot 44 through which the shield may be seen and by having the latter appropriately marked, as indicated by the numerals 50 2—4—8, &c., Fig. 14, the operator can arrange the shield so as to place a title perfectly central under the photographic image. If there be eight letters in the title he would move the shield until the figure 8 appears beneath slot 44. This will bring a window *a* in the shield 4 into register with slots 26—6 four spaces to the left of the center of these slots which is the correct position for the beginning of a title of eight characters. It will be obvious that marks other than numerals may be placed upon the shield 4 for assistance in centrally locating a title.

60 One end of the parts 4—5 is bound with a metal bead 45 which, when drawn up to the teeth of wheels 7—8, prevents the wheels

from further turning as the bead has no notch into which a tooth can enter thus serving as a stop without ripping the teeth on parts 4—5. This stop is also utilized to obtain the space between words, for when 70 curtain 5 is thus positioned no row of letters is before the exposure slots 26—6 and when the button 36 is depressed the spacing shield 4 passes one of its successive positions without the film or plate being impressed 75 with a letter.

In order that the camera may be perfectly light proof the cut out portion of the back forming the part of the tongue 23 which is exterior to the cap 27 will be covered by 80 the usual leather covering of the camera and in the interior of the cap one may, if necessary, place a piece of opaque paper or other covering on the bottom of the chamber and upon which the shutter can glide. 85

To operate the device the wheel 18 is turned by the finger until the proper numeral or mark is seen through opening 44 in the camera back to indicate the position of shield 4 for the first letter of the title. 90 Holding the camera in the left hand with the thumb resting over button 36, the right hand is run along the wheel 17 until the first letter of the title appears at the center of slot 42. (This center is indicated in any 95 suitable manner). This action has placed in register with slots 26—6 a row of letters corresponding to the letter seen through slot 42. The button 36 is now pressed and the shutter 25 moved to uncover slots 26—6 and light is passed through the window of shield 4 that is in register with slots 26—6 and the image of the character beneath this window is photographed on the film. All of the other characters of the line of characters being beneath the opaque part of shield 4 are not photographed. 100

The first character of the title having been exposed to light the button 36 is released and on the return, or closing movement of the shutter 25 the tongue 31 turns the wheel 18 the space of one tooth and the shield is advanced one step bringing the next window therein into position beneath the slots 26—6 to expose the second character of the title to light. The operator now moves wheel 17 until the second character of the title is seen through slot 42 when the button 36 is again pressed and so on until all of the characters of the title have 105 been exposed. 115

Rolls of film, as now made, are furnished with a backing strip of opaque paper, and for my purpose this paper would have openings or windows at regular intervals to permit access to the film to title each view. In Fig. 8, 47 is such a strip of paper, the openings 46 being cut therein at intervals substantially equal to the length of the opening formed by the frame 21—21. There is 120 125

one opening 46 for each of the regular sequential exposure numerals, the latter being, as seen in Fig. 8, placed near one edge of the paper together with "T. F." marks, 5 meaning "title in foreground". The object of the latter is to assure correct adjustment for printing the titles within the pictures, being appropriately placed therefor in the paper. The film carrying spools at opposite 10 ends of the camera operate in the usual manner, the film together with the backing or cover 47 being wound up on spool 19 when the spool is rotated by hand from the exterior of the camera, and when so wound, 15 the appearance of an exposure numeral beneath the red glass 48 in the camera back denotes that an opening 46 has come opposite the slot 6, as well as that a fresh, unexposed, film area has come into position 20 for view exposure. By printing the title while the exposure numeral is beneath the glass, the title will be placed below the picture, and by adjusting the film and cover to bring the nearest T. F. mark beneath the 25 glass after the view exposure is made, the title may be printed on the foreground at a proper distance from the bottom of the view.

In the herein described construction of 30 the camera, it is important that the film shall be shielded from light during the exposure of the letters, and, included in the provision of means for this purpose, I have shown an arrangement of the letter printing 35 aperture, or slot, with respect to the film whereby the former is so situated that light cannot spread within the camera beyond the desired area. Especially when a highly sensitized film is used in the camera is it 40 important that light admitted for the photographing of characters shall not spread beyond the desired area, which, however, may vary somewhat in extent, depending on whether it is opacity or transparency 45 which predominates in the character curtain. In the latter case a larger film portion opposite the slot is liable to be exposed, but, in either case, those film portions farther away from the slot will be shielded, such as 50 for instance the film area opposed to the opening or passage formed by the film-masking frame through which the pictorial exposure is made, or, if the title is printed within the picture area, at least the main 55 portion thereof.

The significance of the combination of 60 certain elements in the camera will readily have been appreciated. As the head-frame, upon light breaking over the inner edges of same near the film during view exposure, causes the sharp definition of the picture boundary in a definite relation to the character printing-position determined by the aperture 6 and more exactly by the detent, 65 there is a joint contribution toward the

proper agreement of picture boundary and the typed line on the part of those elements producing them, and toward the even spacing of each character of the line away from the boundary; and the disposal of these 70 elements adjacent the fixed path of film travel insures the same effect for the selective printing inside or outside the boundary of a picture, as well as for succeeding ones. 75

A modified form of my device is shown in Figs. 17, 18 and 19. In Fig. 17, 50 is a strip which may be of same material as curtain 5, this strip or band carrying two rows of letters, those in one row being adapted 80 to photographically impress the film of the camera; the upper row is for sight and the lower for exposure. The opaque band 51, Fig. 18, lies on top of band 50 and has two windows *a*—*a'*. Both bands are adapted to 85 glide in an appropriate groove forth and back independently of each other. When one of the letters of the upper row of letters on band 50 is seen through window *a* the corresponding letter on the lower row 90 of letters on the band will be in register with the window *a'* and under or over a slot 6 carried by the camera. The admission of light to the slot 6 and to the photographic film or plate is controlled by a shutter 52 95 which normally covers the whole slot 6 but which can be drawn away from the slot, being guided in guides H—I. When a title is to be impressed on the negative the operator sets the band 51 so that the window *a* 100 is placed in the desired position for the first letter of the title. He then moves the band 50 so as to place the desired letter in register with window *a*. The shutter 52, which meanwhile has been covering the slot 105 6, is now withdrawn to admit light through windows *a'* to the letter which is photographed on the film. The shutter is now closed and the band 51 is drawn to bring the window *a'* to proper position for the 110 next letter. The band 50 is now moved until the next desired letter is seen through inspection window *a* when the shutter 52 is operated to admit light as before, and so on.

To facilitate the proper movement of the band 51 for spacing the letters it, the band, may have graduation marks *J* and the camera may carry a stationary pointer *K* which, with the graduation marks, will make it easy to properly move the band 51 115 120 for properly spacing the letters of a title.

If the operator chooses, he can entirely withdraw the shutter 52 and dispense with it, in that case covering and uncovering the opening or window *a'* with the finger with 125 which he manipulates the band 51 while forming words on the film. The band is also adapted to be slid over to the side so the opening may be out of register with the slot 6 in the camera back, thereby entirely 130

- closing the slot, the band alone being sufficient for this. It is of course equally efficacious for use in connection with a letter-carrying element like the curtain 5.
- 5 The curtain, as well as the band, is shown as being arranged to be moved in a straight line of travel opposite a slot, but the curtain will upon movement become deflected or bent by the sliding engagement with the 10 curved end portion of the casing. Nevertheless, when the path of travel of the curtain 5 is viewed as by sighting down upon Fig. 3, it will be seen that it is a straight path or line of movement, hence an expression herein referring to the path or line of movement as being straight does not, within the intended meaning, preclude the bending of the character-carrying material as viewed in another plane.
- 15 20 It will be seen that I have provided a camera which, while it carries a film-masking frame to shadow graphically define the pictorial boundary during view exposure, a character-printing device whereby any person, though he be unskilled in the art of writing, can print a neat line of inscription in definite and pleasing relation with the picture boundary as defined by the frame, particularly its lower member 22, and means 25 whereby the pictorial area is held in a light excluding inclosure so that an inscription may be printed before or after view exposure, it can also be used to print a title directly upon a positive paper print from any 30 35 untitled negative. It is also adapted to serially identify exposures, not merely those of a single film-roll, but progressively throughout a series of rolls, marking exposures in alphabetic order, a utility particularly advantageous in connection with note-taking too extensive to go on the film. To this end the curtain 5 may be appropriately adjusted each time, the slot 42 recording exteriorly the progress in the series, and the 40 45 operator may print a record as he chooses, may, for instance, keep the shield 4 withdrawn from the slot 6 as its teeth or notches, leading all way out to the upper edge, permit its withdrawal, then move the shutter 50 55 to print on the film at once all the characters he has adjusted before the slot. This is advantageous as a line of them would be more conspicuous and easily observed in the dark-room during development and 60 65 would show up very effectually on the narrow margin between successive view exposures without encroaching on the picture area.

It will be understood that the camera embodying my invention, whether such camera is of the type shown, a plate holder, a printing frame, or other holder for photographic sensitized material, need not necessarily be provided with all the features herein described, in order that the formal

characters or types may be selectively adjusted and printed so as to form an inscription in relation with the picture, as the most important part of the photographic inscription device, when considered by itself alone, 70 are the types and an aperture, and by the provision of a suitable adjustive accommodation therebetween an operator is enabled to selectively print letters, figures, sequential records, etc. 75

While the shield 4 is regarded as a valuable auxiliary in connection with the longitudinal alphabetic rows, particularly when operating on highly sensitized film, it will be apparent that the word-forming operativeness of the device shown in Fig. 3 is due primarily to the longitudinal parallel rows whereof each has letters from A to Z, the slot 6, and the adjustability of these rows 80 across the slot for the purpose of selection, the equidistant spacing of these rows from left to right determining the spacing of the letters of the printed word. In connection with the less sensitive photographic print paper, when the device is utilized to print the title directly on the positive print, and as the back extends over to conceal the majority of letters, any person with elementary knowledge of photographic printing would be able by appropriate hand-masking 90 before the slot, in any convenient manner, to cause only desired letters, which he may by sight select out of these rows, to be printed so as to form words on the paper, whereby a large part of the result contemplated by the use of my invention may be obtained without necessarily requiring the presence of all the parts herein shown and described. And this word-forming operativeness of the device, even though the shield 100 105 4 be absent, may apply to the use of film as well as paper, for, whether film be of high or low sensitivity, the actinic value of the light transmitted through the patterns or types would merely depend on the light 110 source, or on the degree of light perviousness of the patterns, or on other conditions well known to those skilled in the art.

The types or patterns being previously formed for the operator's use so that he can 115 form a title or inscription without it being required that he shall possess skill in shaping letters or characters, I have sometimes in the claims designated same as "formal characters" or "formal letters or characters," these terms being intended to signify that the characters (or letters), constituting a feature of the inscription device, are produced otherwise than by the operator's normally operating said device. 120 125

Having thus described my invention I claim as new and desire to secure by Letters Patent:—

1. A photographic camera having an aperture in one of its exterior walls, a shutter 130

for the aperture, a film-masking frame carried in the interior of the camera, adapted and arranged to define the picture boundary in definite relation to the aperture in said wall, and pattern representing a set of the letters constituting the alphabet, movably mounted for adjustment relatively to the aperture and the film.

2. A photographic camera having an element to define on a contained sensitized sheet the area to bear the pictorial impression, type-carrying means carrying the alphabet and movable relatively to the sheet, adapted and arranged to permit the printing of a typographical record at the boundary of the area so defined, and members to exclude actinic light from the larger part of said area while the typographical record is being printed thereat.

20 3. A photographic camera adapted to admit light to a contained sensitized film and having means for shadowgraphically defining on the film the boundary of a pictorial view, an inscription device including material having a series of character formations produced otherwise than in the normal operation of said device, means for impressing upon a film portion through said character formations a series of characters in definite spaced relation with the picture boundary as defined by said boundary defining means, the camera having means for excluding actinic light from all other portions of the film during said impression.

35 4. The combination with a photographic camera body having at the front an opening for view exposure, of a rear covering wall having a lineal opening formation to admit light to the light sensitive sheet of the camera, means movable relatively to the sheet and carrying formal letters or characters comprising the alphabet, adapted to be moved so as to place letters of the alphabet in successive positions along the length 40 of said formation, in register therewith, and means for controlling the admission of light to said sheet through the opening formation in said wall.

5. A photographic camera having in rear of the contained film a wall pierced with a slot, transparent material having thereon formal letters of the alphabet disposed in a series of straight parallel adjacent rows, said material being mounted for adjustment 55 independently of the film so as to bring selected letters into successive positions along the slot, means for so adjusting said letter-carrying material, means for admitting light to print said letters on the film, and 60 an element to define the pictorial area, comprising a frame carried in front of the film and forming an opening through which light may be admitted from the front of the camera.

65 6. A photographic camera having an

opening through which the pictorial exposure is made, and a second opening arranged to permit the exposure of the sensitized film in the interior independently of light admitted through the first-mentioned opening, an element bearing formal characters arranged to make up one or more sets of the letters which constitute the alphabet, said element being suitably mounted for the photographic printing of characters by exposure through the second opening and mounted for adjustment relatively to the film portion in position for exposure through the second opening, means for admitting light at will to the film so as to print a line of characters thereon through the exposure of the film to said element, and means for shielding all other portions of the film from light during the printing of characters.

7. A photographic camera furnished with a light pervious opening opposed to the sensitized film in the interior, and flexible material provided with formal characters representing the alphabet, means to guide the movement of said material along a straight line of travel opposite and relatively to said opening and said film, a member positioned for movement opposite the opening to cover and uncover a film portion which is beneath, and means whereby actinic light is wholly excluded from all other portions of the film while said portion is uncovered.

8. A photographic camera having members to exclude actinic light from portions of a contained sensitized sheet, including an apertured wall, and in the interior a frame forming an opening through which a portion of said sheet may be exposed to light, 100 said frame being adapted and arranged to mask another portion of the sheet during said exposure, said opening and an aperture in said wall being so disposed relatively to the sheet that light may be admitted to the 105 sheet through the opening without having to pass through the aperture, material carrying a plurality of formal characters representing the alphabet, adjustably mounted opposite said wall and movable 110 relatively to the sheet, so arranged that characters may be moved into accurate register with the aperture while actinic light is excluded from that portion of the sheet which is opposite the aperture, a member 115 operable at the will of the operator to cause character impressions upon said portion by means of the characters on said material, all being so adapted and arranged that all other portions of the sheet will be protected 120 against actinic light during said impression.

9. The combination with a photographic camera body having at the front an opening for view exposure, and an opaque back extending over the sensitized element, said 130

back being provided with a passage for light, of a substantially opaque, flexible, sheet also extending over said element and provided with a passage for light, said sheet being mounted to permit the adjustment of its said passage to the one in the back, material provided with character formations, so adapted that light may pass therethrough to print characters onto said element, said material being movably mounted on the rear of the camera to permit the selective placing of character formations opposite both said passages.

10. A photographic camera comprising a casing having an opening to admit light for view exposure, and an aperture in its rear wall to admit light for the printing of characters upon a sensitized sheet carried between said aperture and said opening, and material provided with a set of formal characters constituting the alphabet, suitably mounted adjacent said wall for adjustment relatively to the aperture and the sheet, so adapted that a character of the set may be 25 in register with the aperture while others thereof are out of register with the aperture.

11. The combination with a photographic camera, of suitable material opposed to its sensitized film and provided with rectilinear rows of the characters which constitute the alphabet, so adapted that light can penetrate therethrough to print characters onto said film by photographic exposure, a covering member extending over the film and 35 provided with a lineally formed opening permeable to light, said opening being so placed and adapted that a plurality of characters may simultaneously have exposure position opposite the opening, stationary guide 40 members whereby said material is guidably mounted for a rectilinear movement across the film portion opposed to said opening, a member positioned for movement opposite this opening to exclude and admit light to 45 said film portion, means for shielding from light all other portions of the film while light is admitted by said member, and a stationary frame forming an opening to permit the exposure of the film from the front 50 of the camera.

12. The combination with a photographic camera furnished with a slot to admit light to the light sensitive sheet of the camera, of a movable means carrying permanent letters 55 or characters adapted to register with said slot and representing one or more sets of the letters which constitute the alphabet, said means being adapted to permit an operator to place selected letters at different points of 60 location along the length of the slot in order to form a word or words on said sheet by photographic impression, a means for controlling the admission of light through said slot to the slot-opposed part of said sheet in

order to photographically expose the sheet 65 to letters or characters on said means, and means for excluding actinic light from all other parts of the sheet during said exposure.

13. The combination with a photographic 70 camera, of means carrying letters or characters adapted to permit an operator to place selected letters at different points of location over the sensitized sheet of the camera in order to form a word or words on said sheet 75 by photographic impression, an actinic light impervious shield carried by said camera over said sheet and furnished with a light pervious opening, means for bringing any selected one of said letters or characters in 80 register with said opening in said shield, a means for controlling the admission of light through said opening to part of said sheet in order to photographically expose the sheet to said letter or character, means for shielding all other parts of the sheet from light during said exposure, and means for advancing said shield so as to bring its said opening in a series of successive positions 85 progressively in the direction graphically determined by the position in which the initial letter of the word to be printed is placed.

14. A photographic camera provided with a lineal opening formation to admit light to a contained sensitized sheet, material provided with characters adapted to be light-printed on said sheet and representing one or more sets of the letters which constitute the alphabet, said material being movably adapted to permit the placing of selected 95 letters in a series of printing positions along the line of said opening formation, the characters being carried so as to permit the operator to light-print upon said sheet a graphic sequence of letters differing in sequence from that of the characters comprising the alphabetic set, a member arranged to shield the sheet against light from said opening formation and adapted to be moved to expose it to light therefrom, means for 100 shadowgraphically defining upon said sheet the area to bear the pictorial impression, and means for shielding the larger part of said area from light during the printing of characters.

15. A photographic camera having against the face of the contained sensitized medium a frame forming an opening through which a portion of said medium is made accessible for being impressed with a pictorial view, 110 said frame being adapted to mask another portion of the medium during said impression, a covering member adapted to extend adjacent to said medium and over said opening so as to cover a face of said first-mentioned portion, said member being provided with an aperture, and an element bearing a set of formal characters and so mounted on 115 120 125

said member as to permit an adjustment of characters relatively to said aperture whereby a character of the set may be in register with the aperture while other characters of 5 same set are out of register therewith.

16. The combination with a photographic camera body having a film-masking frame adapted and arranged to define the boundary of a pictorial view during view exposure, of a covering rear wall extending over said frame, the wall being provided with a lineally formed opening to admit light and having a definite position with respect to 10 said frame, material having character formations, representing the alphabet, suitably mounted on the camera for adjustment relatively to said frame, said opening, and said film, means on the camera to guide the movement of said material along a definite path 15 of travel relatively to said frame, and an adjustable member mounted for movement opposite the opening to photographically expose the film to said character formations.

17. A photographic camera having at the front an opening to admit light for view exposure, and in the rear a wall provided with an elongated opening formation to pass light to a contained sensitized sheet, a shutter movable opposite this opening formation, adjustable material carried adjacent said wall, said material having letters thereon, the letters being arranged in a number of rectilinear parallel rows, said opening formation being so arranged that 35 it extends transversely with respect to the rectilinear rows, each of said rows comprising the letters which constitute the alphabet.

18. A photographic camera furnished 40 with an opening to admit light to a contained sensitized film, and material slidably mounted opposite said opening so as to be movable along a straight line of travel relatively to the opening and the film, means 45 whereby said material is so mounted, this material being flexible and provided with formal characters representing the alphabet, so adapted that light may pass therethrough to photographically transfer the 50 characters to said film, a member arranged to shield the film against light from said opening and operatively adapted to be moved to expose part of the film to light therefrom in order to photograph the characters placed opposite the opening, and means whereby actinic light may be wholly excluded from all other parts of the film during said exposure.

19. The combination with a photographic 60 camera furnished with an opening to admit light, of a strip of material provided with character formations representing letters of the alphabet, means on the camera to guide the movement of said material along a

straight path of travel opposite the opening, means on the camera for visually indicating which letter of the alphabet is in register with the opening, and means for holding said strip in predetermined successive positions along said path of travel in 65 order that the letters may be accurately placed with respect to said opening, and a member arranged to shield the sensitized element of the camera against light from the opening and movably mounted to expose it to light therefrom, in order to print 70 the letters.

20. The combination with a photographic camera furnished with an aperture, of a flexible tape mounted on the camera and 80 provided with character formations, means on the camera to guide the movement of said tape along a straight line of travel opposite said aperture, and detent means carried by the camera and co-operatively connected 85 with said tape to favor its adjustment into predetermined successive positions along said line of travel in order to accurately place the character formations with respect 90 to the aperture.

21. A camera adapted to admit light to its contained sensitized film and comprising members forming an inclosure for the film to shield portions thereof against light, one of said members being provided with an exposing aperture, the camera having in its interior a film-supporting frame masking a portion of the film and forming an exposure opening larger than said aperture, the camera carrying in proximity to the film a 100 character-bearing element having letters constituting the alphabet, said element being adjustable independently of the film and arranged to be moved opposite the aperture.

22. A photographic camera adapted to admit light to its sensitized film and having a film-masking frame forming an opening through which the photographic pictorial exposure is made, said frame being adapted and arranged to shadowgraphically define 110 the pictorial area upon said film during said exposure, means for printing a line of characters onto a film portion adjacent to said frame, said means including an element having character formations and the element being mounted on the camera for movement relatively to said film, and also including means whereby the operator may at will cause the impression upon the film of said character formations, so adapted that only 115 a single character may be printed on the film at one time, the camera having means for shielding from light during the printing of characters the larger part of the film-area opposed to said opening.

23. A camera having at the front an opening for view exposure, and in the rear a wall extending over said opening, said wall be-

ing provided with a lineally formed and transversely placed passage for light, material provided with character formations, so adapted that light can penetrate therethrough to print characters onto the sensitized film of the camera, members to guide the movement of said material in a straight path of travel opposite said passage and longitudinally with said wall, said material being thereby slidably mounted for movement relatively to said film, said character formations being arranged in a series of straight rows extending longitudinally with said wall, and means for controlling the admission of light to the film portion underlying said passage.

24. A photographic camera provided with an opening to admit light to the sensitized film in the interior, a pair of relatively adjustable members, one of said members being provided with characters adapted to be photographically transferred to said film, this member being suitably carried on the camera to permit the adjustment of characters relatively to the film and their transfer thereto by photographic exposure through said opening, the other one of said members being adapted and arranged to shield part of the film against light from said opening but provided with a passage through which the photographic exposure may be made in order to transfer the characters to the film portion in position for exposure through said opening, means for shielding all other portions of the film from light during said exposure, a frame adapted and arranged to shadowgraphically define the boundary of a pictorial view on said film, and means to guide the movement of said members in a definite path of travel relatively to said frame.

25. The combination with a photographic camera having an elongated opening to admit light to the sensitized element, of material provided with photographically transferable characters, mounted on the camera for movement relatively to said opening, a member mounted opposite the opening and movably adapted to admit light to said element progressively in a continuous direction along the length of the opening, said member being substantially impervious to actinic light but provided with a restricted passage for light, said passage being so proportioned to the characters on said material that light may be admitted to photograph on the film at one time only a single character in position opposite the opening.

26. A photographic camera comprising a casing provided with an aperture and carrying a pair of relatively adjustable superposed tapes, means to guide the movement of said tapes along a straight line of travel opposite the aperture, one of said tapes being provided with a line of photographically

transferable characters so placed that characters may register with the aperture, the other tape being of material which is obstructive to the passage of actinic light therethrough but being provided with a light pervious opening adapted to register at one time with only a single one of said characters registering with the aperture.

27. A photographic camera provided with an opening to admit light to a contained sensitized film, the camera carrying a pair of tapes, means whereby said tapes are guidably mounted for a straight line of movement opposite said opening, one of said tapes carrying a line of characters adapted to be photographically transferred to said film, the other tape being adapted to shield an underlying film portion against light but provided with a light pervious opening suited to transmit light to the film to photograph only a single character at one time, and means for determining the accurate adjustment of the last-mentioned tape into a series of definite successive positions.

28. The combination with a photographic camera provided with an opening to admit light to a sensitized sheet in the interior, of a pair of relatively adjustable members mounted on the camera for movement opposite said opening, one of said members being provided with character formations adapted to photographically impress said sheet, the other of said members being adapted to shield part of the sheet against light from said opening but provided with a restricted passage through which light may pass to impress the sheet through said character formations, and means for moving said last-mentioned member with a step by step movement.

29. The combination with a photographic camera furnished with a slot to admit light to a light sensitive film carried in the interior of the camera, of a movable actinic light impervious means furnished with a light pervious opening and adapted to be moved so as to bring said light pervious opening in successive positions along the slot, in register therewith, a means for determining the position in which said opening is placed, a means carrying letters or characters adapted to be moved so as to place any one letter of the alphabet, or any character, in register with said opening registering with said slot, and means for controlling the admission of light through said opening to said film.

30. The combination with a photographic camera furnished with a slot to admit light to a light sensitive film carried in the interior of the camera, of a movable actinic light impervious means furnished with a light pervious opening and adapted to be moved so as to bring said light pervious opening in successive positions along the slot, in register therewith, a means for determining

105

- the position in which said opening is placed, a means carrying letters or characters adapted to be moved so as to place any one letter of the alphabet, or any character, in 5 register with said opening registering with said slot, means for visually determining the letter or character thus placed, and means for controlling the admission of light through said opening to said film.
- 10 31. The combination with a photographic camera furnished with a slot to admit light to a light sensitive film carried in the interior of the camera, of means for opening or closing said slot, a letter or character carrying means adapted to be moved so as to place any letter of the alphabet, or any character, in successive positions along the slot, in register therewith, a movable actinic light impervious shield furnished with a 15 light pervious opening, and a means, operated by said slot opening and closing means, for actuating said shield to bring its opening into successive positions along said slot, in register therewith.
- 20 32. The combination with a photographic camera furnished with an opening to admit light to a contained film, of an element movably mounted opposite said opening and provided with character formations, a member 25 movably carried adjacent to said element and adapted to shield the film against light from said opening but provided with a restricted passage through which light may pass to expose the film to a character formation, means for actuating said member to move it relatively to said film, and means coöperatively arranged with said moving means for controlling the exposure of the film through the passage in said member.
- 30 33. The combination with a photographic camera embodying a casing furnished with an elongated opening, of material provided with character formations disposed in a series of straight parallel rows, means on 35 said casing to guide the movement of said material along a straight path of travel opposite said opening and at a right angle to the length of the opening, said material being thereby slidably mounted for movement relatively to the sensitized medium, a closure for the opening, and hand-operable means coöperatively arranged with said material to move same along said path of travel.
- 40 34. A photographic camera adapted to admit light to its sensitized film and having a frame forming an opening through which the photographic pictorial exposure is made, said frame serving to define the pictorial area upon said film, means for adjusting characters into definite printing positions relatively to said frame, said means having a set of characters to impress the film, and another set of characters to guide the adjustment of the first-mentioned set, and de-
- tent means coöperatively adapted therewith to determine the accurate adjustment of the characters which are to impress the film, the camera having means for shielding from light during the printing of characters the 70 larger part of the film area opposed to said opening.
- 45 35. A photographic camera having a frame forming a light passage through which the photographic pictorial exposure 75 is made, said frame being adapted and arranged to mask a portion of the contained sensitized sheet so as to define thereon the boundary of a pictorial view during said exposure, the camera carrying a member 80 furnished with a lineally formed opening and having a definite position adjacent said frame, suitable material carried opposite the opening and movable relatively to said sheet, said material being provided with characters adapted to be reproduced on the sheet when in operative position opposite the opening, said characters being disposed in a series of straight parallel adjacent rows extending at right angles to the length or 85 line of the opening, said material being slidably mounted adjacent said opening so as to permit the movement of said rows of characters in a direction transverse to the length or line of the opening. 90
- 50 36. A photographic camera having a lineally formed opening to pass light to a portion of a contained sensitized sheet, a shutter therefor, and light pervious patterns representing letters of the alphabet disposed in a 100 series of straight parallel adjacent rows extending at right angles to the line of the opening, said patterns being mounted on the camera opposite said opening so as to permit their movement along a straight path 105 of travel in a direction transverse to the line of the opening.
- 55 37. The combination with a photographic camera, of flexible material movably mounted thereon and provided with characters 110 adapted to be reproduced upon a sheet carried in the interior, the camera having an opening to permit the reproduction upon said sheet of said characters, means for guiding said material in a definite path of 115 travel opposite said opening, means for holding said material in predetermined successive positions in said path of travel, and means for bending said material toward said sheet. 120
- 60 38. The combination with a film-roll camera embodying a casing inclosing the sensitized film, and having an end portion curving around the film-roll, of flexible material opposed to said film and provided with characters representing the alphabet, said characters being adapted to be reproduced on the film, and means on the casing whereby said material is movably mounted 125 and guided appropriately for a sliding en- 130

gagement along the curvature of said end-
portion in order to curve the material around
the film-roll, the casing having an opening
opposed to said material to permit the repro-
5 duction upon the film of said characters.

39. A photographic camera embodying a
casing comprising a plurality of walls to
inclose the sensitized element, one of said
walls being provided with an opening to ad-
10 mit light to said element, a shutter for the
opening, a movable push-button situated on
one of said walls and operatively connected
to work said shutter, and a member pro-
vided with photographically transferable
15 characters, mounted for movement opposite
said opening.

40. The combination with a photographic
camera adapted for the movement of a sensi-
tized film in the interior and provided with
20 an opening to admit light and a member for
holding characters opposite said opening, of
a flexible, opaque, covering sheet for said
film, arranged for movement in unison with
the film independently of said member and
25 adapted to limit the passage of light to a
predetermined film area.

41. A photographic camera adapted to ad-
mit light to its sensitized film and having
means for winding said film therein, a flex-
30 ible opaque protective cover arranged to be
wound together with the film, material hav-
ing characters representing the alphabet,
said material and said cover being so ar-
ranged relatively to the film that the latter
35 may be accessible for impression by means
of said characters while the cover extends
over the film to shield portions thereof
against light.

42. The combination with a camera hav-
40 ing an opening to admit light to its sensi-
tized film, of material having formal char-
acters constituting the alphabet, said mate-
rial being mounted for movement opposite
said opening independently of said film, a
45 flexible sheet superposed on the film, the
film and the sheet being arranged for move-
ment in unison, said sheet being adapted to
pass light from said opening to the film, for
the printing of characters.

50 43. The combination with a photographic
camera having means for winding a sensi-
tized film therein, and means whereby char-
acters may be formed on the film, of a flexi-
ble cover superposed on the film, said cover
55 having an incision arranged to render a film
portion accessible for the formation of char-
acters thereon independently of said cover.

44. The combination with a camera body
adapted to contain a roll of film, of a flexi-
60 ble protective cover adjacent to the film, a
covering wall extending over said film and
cover and provided with an opening to ad-
mit light, said flexible protective cover be-
ing adapted and arranged to only partly
65 cover one face of the film so that part of

same face of the film is left uncovered there-
by and may be opposed to the opening in
said wall, and a character-bearing element
adapted for the photographing of characters
on the uncovered part of the film by light 70
admitted through said opening.

45. The combination with a photographic
camera having a flexible light sensitive film
arranged to be moved within the camera,
and means for photographically printing a 75
line of characters transversely across the
film, of an actinic light impervious cover ad-
jacent to the film and arranged to be moved
therewith, said cover being provided with
light pervious openings or windows coöper- 80
atively adapted with said means to permit
the printing of a line of characters trans-
versely across the film.

46. A photographic camera adapted for
the insertion of a film roll and having a 85
frame forming an opening to define the
boundary of the pictorial area on the film,
a rear wall provided with a passage through
which light may pass to the film, a flexible
protective sheet arranged to be wound to-
90 gether with the film and having a cut where-
by a limited sensitized film area is rendered
accessible for the production of indicia
thereupon, said sheet being adapted to ex-
tend over said opening in the frame to cover 95
the corresponding film portion while the
said limited film area is in exposure position
opposite said passage, and a movable shut-
ter carried on the rear of the camera to con-
100 trol the admission of light through said
passage to said film area.

47. A camera having in front of a con-
tained sensitized film an opening for view
exposure, and in the rear of said film an in-
scription device whereby characters may be 105
printed on the film, said device comprising
a member having an opening therein to ad-
mit light to the rear of the film, the member
serving as a rear wall of the camera, ma-
terial movably mounted for adjustment rela-
tively to the film and the opening, said ma-
terial being provided with characters pro-
duced otherwise than by the normal opera-
tion of said device and adapted for registry
110 with the opening, the device including a
closure for said opening.

48. A holder for a sensitized photo-
graphic sheet, said holder being furnished
with a lineal opening formation opposed to
a sensitized sheet contained in the holder,
and adjustably mounted character-carrying
material carried adjacent this opening for-
mation, the characters being light pervious
and arranged so as to form a number of rec-
tilinear rows of characters, said lineal open-
ing formation being so disposed that its line
extends transversely with respect to said
rectilinear rows, each of said rows contain-
ing the letters constituting the alphabet. 120

49. A photographic camera having an 130

- opening to admit light for pictorial photography on a contained sensitized sheet and an auxiliary opening disposed toward one side of said first-mentioned opening, a character-bearing member mounted for movement opposite the auxiliary opening, the characters on said member being adapted for their reproduction on the sheet and representing a set of the letters constituting the alphabet, and detent means coöperatively adapted with said character-bearing member to enable the accurate adjustment of succeeding letters in the alphabetic set in a definite position opposite the auxiliary opening.
50. A photographic camera adapted to contain a sensitized film and having a frame masking a portion of the film to define thereon the area to bear a pictorial impression, said frame being arranged to serve as a front support for the film, the camera having a light passage arranged to pass light to a film portion near the boundary of the area defined by said frame, a movable element bearing a set of characters, this set being made up of a sample of each of the letters which constitute the alphabet, said characters being adapted to be light-printed on the film when in exposure position opposite the passage, said character-bearing element being adapted and arranged with respect to said passage so as to permit the moving into said exposure position, at separate times, of single ones of the letters comprising said set.
51. A camera adapted to contain a sensitized photographic film, and having means to define thereon the area to bear the pictorial impression, the camera comprising
- members arranged to inclose the film to exclude actinic light from portions thereof, material movable relatively to the film and carrying the alphabet in characters adapted to be reproduced on the film, the camera having an opening opposed to said material to permit the reproduction on the film of individual characters on the material, all being so arranged that characters may be reproduced one at the time upon a limited film portion near the boundary of said area while actinic light is excluded from all other portions of the film.
52. A camera adapted to contain a sensitized photographic film and having means to define thereon the area to bear the pictorial impression, the camera comprising members arranged to inclose the film to exclude actinic light from portions thereof, material movable relatively to the film and carrying the alphabet in characters adapted to be light-printed on the film, the camera having an opening opposed to said material to admit light to the film for the printing of said characters, all being so adapted and arranged that characters may be light-printed one at the time upon a film portion near the boundary of said area while actinic light is excluded from all other portions of the film, and an additional member mounted for movement opposite said opening to exclude and admit light to the film portion exposed through said opening.

EINAR LESCHBRANDT.

Copies of this patent may be obtained for five cents each, by addressing the "Commissioner of Patents
Washington, D. C."

It is hereby certified that in Letters Patent No. 1,278,692, granted September 10, 1918, upon the application of Einar Leschbrandt, of Philadelphia, Pennsylvania, for an improvement in "Photographic Cameras," errors appear in the printed specification requiring correction as follows: Page 4, line 37, for the word "in" read *is*; page 6, line 22, for the words "shadow graphically" read *shadowgraphically*, (one word;) page 7, line 5, for the word "pattern" read *patterns*; and that the said Letters Patent should be read with these corrections therein that the same may conform to the record of the case in the Patent Office.

Signed and sealed this 11th day of March, A. D., 1919.

[SEAL.]

R. F. WHITEHEAD,

Acting Commissioner of Patents.

Cl. 95—1.1.
